[57] ABSTRACT

A slidably shiftable closure and ventilating panel unit comprised of alternate air impervious, translucent panel sections and air pervious, ventilating panel sections is suspended on a guide track over spaced apart openings separated by solid wall sections of an upright wall structure. The panel unit is slidably shiftable back and forth on the guide track between an open position in which the ventilating panel sections are aligned over the openings and a closed position in which the air impervious panel sections are aligned over the openings in position to be pulled in tightly against weather stripping around the openings by latch means affixed to the upright wall structure inside of the openings. The air impervious panel sections are comprised of an opaque sheet of thermal insulating material having at least one through aperture therein of decorative configuration and an overlying sheet of translucent, air impervious material.

CLOSURE AND VENTILATING WALL STRUCTURE

BACKGROUND OF THE INVENTION

Various types of combined window and screen structures have been developed for alternately closing or opening a plurality of spaced apart openings in a dwelling wall by the use of a slide unit comprised of alternate glass and screen panels, the slide unit being shiftable with respect to the dwelling wall so as to align either the glass panels or the screen panels with the openings. Such prior art closure and ventilating structures have generally incorporated a pair of spaced apart guide tracks in which the opposite, longitudinal edges of the slide unit are restrainably engaged for sliding movement. Such a structural approach for the glass and screen slide unit has necessarily required elaborate and expensive sealing devices for maintaining a tight, weather seal of the glass panels around the dwelling openings when the slide unit is shifted to position the glass panels in alignment with the openings. See, for example, U.S. Pat. No. 3,289,738.

I have developed a combined closure and ventilating wall structure which overcomes the aforesaid difficulties and provides a unique decorating effect by the use of a freely suspended slide unit having alternate ventilating panel sections and air impervious, insulating panel sections of decorative design.

BRIEF SUMMARY OF THE INVENTION

The closure and ventilating panel structure of this invention is particularly characterized by a slide panel unit which is freely suspended in such a way that it can be quickly and easily shifted between so-called open and closed positions selectively aligning its alternate translucent closure panel sections or air pervious ventilating panel sections over openings in an upright wall without interference with weather stripping around the openings, while permitting tight, sealing engagement with the weather stripping by the use of releasable latch means engaged after the panel unit is shifted. The closure panel sections are constructed in such a way as to provide a distinctive decorating effect when slidably positioned over the wall openings in tight, sealing engagement therewith.

These basic objectives and advantages have been realized by suspending the slide panel unit only at its upper end in a guide track extending above spaced apart openings in a wall so that the side panel unit is free hanging at its bottom end. Releasable latches attached to solid wall sections on opposite sides of the wall openings are utilized to pull the closure panel sections in tightly against weather stripping extending around the periphery of each opening when the slide panel unit is shifted to its closed position. When the latches are released, the free hanging slide panel unit will tend to swing outwardly from the wall, with the result that it can be easily shifted on the guide track without interference with or damage to the weather stripping to position the ventilating panels over the wall openings. In order to insure that the slide panel unit will be able to swing outwardly away from the weather stripping on the building wall when the latches are released, pivot brackets attached to the upper end of the slide panel unit are utilized to suspend it from the overhead guide track.

A further advantageous feature of the aforesaid slide panel unit resides in the positioning of attachment devices for the closure panel latches within recesses on opposite sides of the inside faces of the closure panel sections. This feature insures that there will be no inwardly protruding obstructions on the sliding panel unit which would rub against and damage the weather stripping around the wall openings when the slide panel unit is shifted between its open and closed positions.

10 The aforesaid latches for the closure panels preferably take the form of spring-loaded, pivotal arms mounted on opposite sides of each wall opening in such a way that they may be pivoted inwardly to over center locking positions wherein they pull the closure panels inwardly in very tight, sealing engagement with the weather stripping around the wall openings.

15 A particularly advantageous decorative effect is derived from the structure of the air impervious, closure panels provided on my sliding panel unit. Each of the closure panels is comprised of an opaque, thermal insulating sheet having at least one through aperture of decorative configuration and covered on at least one side by a sheet of air impervious, translucent material. By virtue of this panel construction, weather elements will 20 be excluded by the air impervious sheet and light may only pass through the decorative apertures in the opaque insulating sheet.

25 These and other objects and advantages of my invention will become readily apparent as the following description is read in conjunction with the accompanying drawings wherein like reference numerals have been used to identify like elements throughout the several views.

BRIEF DESCRIPTION OF THE DRAWINGS

30 FIG. 1 is a perspective view of a building enclosure having the sliding closure and ventilating panel unit of this invention mounted thereon;

35 FIG. 2 is a top, plan view, partially in section, of the closure wall and sliding panel unit of FIG. 1;

40 FIG. 3 is a fragmentary, horizontal section view of one of the air impervious panel sections taken along lines 3—3 of FIG. 1;

45 FIG. 4 is a fragmentary, horizontal section view of one of the air pervious, ventilating panel sections taken along lines 4—4 of FIG. 1;

50 FIG. 5 is an end, elevation view, partially in section, of the side panel unit and one of the wall openings;

55 FIG. 6 is an exploded, perspective view showing the manner of attachment of the ventilating panel sections to the closure panel sections; and

FIG. 7 is a fragmentary, horizontal section view taken along lines 7—7 of FIG. 1 and showing one of the latch mechanisms at the corner junction of one of the wall apertures and one of the air impervious, closure panels.

DESCRIPTION OF THE PREFERRED EMBODIMENT

60 Referring now to the drawings, I have shown in FIG. 1 a building 1 having an upright wall 2 on which the closure and ventilating panel unit of this invention has been mounted. Upright wall structure 2 has a plurality of fixed, spaced apart solid wall sections 4 defining therebetween a plurality of spaced apart openings 6. For the purpose of selectively closing and providing ventilation through openings 6, I have provided a shiftable panel unit generally designated by reference nu-

meral 8. This panel unit is shiftably mounted for lateral movement back and forth along wall 2, as indicated by the arrows in FIG. 2, on an overhead track 10. It is to be understood that my sliding panel may be utilized on any type of building or dwelling where it is desired to provide selective closing or ventilation by means of a plurality of spaced apart openings in a building wall. For example, I have found my sliding panel unit particularly useful and effective on a wall of an enclosed swimming pool intended for year-around use, for the purpose of providing ventilation and natural lighting through one wall of the swimming pool enclosure.

Guide track 10 is mounted as shown in FIGS. 1 and 5 above opening 6 on upright wall 2 in a direction coextensive with the longitudinal extent of wall 2, although various types of guide tracks may obviously be utilized, I have found it particularly satisfactory to utilize a guide track 10 of inverted, U-shape as shown in FIG. 5 having inwardly extending bottom flanges 10a. Track 10 is supported on wall 2 by a plurality of spaced apart hanger brackets 12 which hook under one of the horizontal guide flanges 10a of track 10 as shown in FIG. 2. The manner in which panel unit 8 is shiftably supported on track 10 is described in detail below.

Panel unit 8 is comprised of a plurality of alternate air impervious, heat insulating panel sections 14 and ventilating panel sections 16 which are air pervious. As may best be understood by reference to FIGS. 3 and 6, each of the air impervious or closure panel sections 14 is mounted on a frame assembly of generally rectangular configuration comprised of a plurality of angle iron members 18 joined together at intersecting corners, as by welding, fasteners, or other suitable means. Abutting against the vertically extending flange faces of the four angle iron members 18 is a first air impervious, translucent sheet 22. An opaque, thermal insulating sheet 20 lies against the outer face of sheet 22 and is substantially coplanar and coextensive therewith. A second translucent, air impervious sheet 23 identical to sheet 22 lies against the outer face of opaque sheet 20. It will be thus seen that opaque insulating sheet 20 is sandwiched between inner and outer air impervious sheets 22 and 23. This assembly of sheets 20, 22 and 23 is held in place against angle iron members 18 by four outer hold-down strips 24 secured as shown to angle iron members 18 by bolts 26. Sheets 22 and 23 are preferably translucent Fiberglas. Sheets 20 may also be formed from various types of material. I have found polyurethane to be particularly effective because of its heat insulating and opaque qualities. In order to insure that the panel sections 14 are air and weather tight, the joints between air impervious sheets 22, 23, and angle iron members 18 as well as hold-down strips 24 are sealed by any suitable cement or caulking compound as indicated at joints 28, 29 in FIG. 3.

Each of the opaque insulating sheets 20 has one or more apertures 30, 30a cut therethrough in the shape of a desired decorative pattern. For example, as is indicated in FIG. 1, star shaped apertures 30 and fish shaped apertures 30a may be utilized. Since insulating sheets 20 are opaque, it will be appreciated that translucent sheets 22 and 23 will permit the passage of light only through apertures 30 and 30a in sheets 20. Thus, natural or artificial lighting may be utilized to outline and emphasize decorative apertures 30 and 30a to provide a distinctive decorating effect.

Ventilating panel sections 16 are likewise assembled on a generally rectangular frame comprised of four angle iron members 32 joined together at their ends. Because of the enclosure requirements for swimming pools in many states, I have used cyclone fencing 34 in combination with insect resistant screen 36 on each of the ventilating panel sections 16. For the purpose of holding cyclone fencing 34 and wire section 36 against the vertical flanges of angle iron support members 32 I have utilized four retention bars 38 in combination with four hold-down strips 40. As is the case with hold-down strips 24 utilized on closure panel sections 14, bars 38 and hold-down strips 40 are coextensive with angle iron support members 32, and with respect to ventilating panel sections 16 are attached thereto by bolts 42 shown in FIG. 4. Retention bars 38 extend through the end loops of fencing 34 as shown at the corners of the rectangular frame assembly and thereby serve to hold fencing 34 securely in place between angle iron members 32 and hold-down strips 40. For application other than swimming pools where positive barriers are not required over the access openings to the pool, fencing 34 may obviously be dispensed with and each of the ventilating panel sections 16 may incorporate wire screen 36.

For the purpose of suspending panel unit 8 from track 10 for shifting movement thereon, I utilize hanger assemblies which are attached to the top of closure panel sections 14. Each of these hanger assemblies includes a double wheeled roller unit 44 having inner and outer rollers 44a and 44b which ride on bottom flanges 10a of track 10 in the manner shown in FIG. 5. A bolt 46 is threaded into the center of each of the roller units 44 and extends through the top of a U-shaped bracket 48 shown in FIGS. 5 and 6. A second, U-shaped swivel bracket 50 is pivotally attached to a pivot pin 52 extending through bracket 48. Swivel bracket 50 is welded to a right-angle weld bracket 54 secured by welding or other suitable means to the top flange face of angle iron members 18.

Ventilating panel sections 16 are removably attached to closure panel sections 14 by means of laterally extending studs 56 having enlarged heads as shown in FIG. 6 and secured to the upright angle iron members 18 on both sides thereof. Complimentary keyhole slots 58 are formed in the abutting faces of angle iron support members 32 of ventilating panel sections 16 and slip over studs 56. In this manner, panel sections 14 and 16 are held together and slide back and forth on guide track 10 as a unitary assembly. This unitary panel assembly 8 is free hanging at its bottom end and thus may be swung outwardly away from upright wall 2 about the horizontal axis defined by pivot pins 52 of swivel brackets 50. This free, pivotal suspension of panel unit 8 provides a particular advantage in clearing the outer face of wall 2 for the unimpeded lateral shifting of panel unit 8 back and forth on track 10.

For the purpose of securing panel unit 8 tightly in place against the outer face of wall 8, particularly when closure panel sections 14 are aligned with opening 6, I have provided latch devices attached to solid wall sections 4 inside of each of the openings 6 on opposite sides thereof. These latch devices or mechanisms preferably take the form of pivotal arms 60 having bifurcated inner ends as shown in FIG. 5 attached to mounting brackets 62a, 62b. These mounting brackets are affixed to the upright, opposed side faces of wall sections

4 defining the opposite sides of openings 6. Pivot pins 64, 64a serve to attach the bifurcated ends of latch arms 60 to mounting brackets 62a and 62b and define vertical axes about which arms 60 are pivotal in a generally horizontal plane substantially normal to the plane of panel unit 8. Each of the latch devices preferably incorporates a coil spring 66 which is releasably engageable with cooperating attachment means provided on the opposite sides of each of the closure panel sections 14. Such attachment means are contained within recesses 68 formed in angle iron support members 18 and sheets 20 and 22 of panel sections 14 and may preferably take the form of pins 70 extending transversely across recesses 68 as shown in FIG. 5. Springs 66 are hooked over pins 70, and may readily be released therefrom when it is desired to unlatch panel unit 8 and shift it laterally on track 10. The inner ends of springs 66 are connected to a coupling device comprising a turnbuckle 72 having longitudinally adjustable bolts 72a and 72b on its opposite ends. One end of each of the springs 66 is attached to outer turnbuckle bolt 72a; and inner turnbuckle bolt 72b has its hooked end attached around a pin 74 affixed to the bifurcated end of each latch arm 60. It is to be noted that coupling pins 74 are affixed to latch arms 60 at a point outwardly thereon from pivot pins 64, 64a where the inner ends of arms 60 are attached to the side walls of openings 6. This arrangement provides an over center, snap lock type of latch mechanism. In FIGS. 5 and 7, latch arms 60 are shown in their inwardly pivoted locking positions wherein springs 66 are placed in tension. Arms 60 snap into their locked positions when coupling pins 74 pivot inwardly past an over center position with respect to the pivotal axis defined by pivot pins 64, 64a.

It is to be noted that a pair of vertically spaced latch devices as described above are positioned adjacent to the top and bottom ends of openings 6 on both sides of the openings so as to pull both the upper and bottom ends of panel unit 8 tightly against the outer face of wall 2. The upper and lower latch devices of each pair of latches mounted on each side of openings 6 are identical, and are shown in FIGS. 5 and 7 respectively. Recesses 68 and attachment pins 70 contained therein are located at the top and bottom of each closure panel 14 on opposite sides thereof in alignment with the pairs of vertically spaced latch devices for engagement by the outer ends of springs 66.

A facing 76 of cork or other suitable material may be placed on the side wall portions of wall sections 4 defining the opposite sides of openings 6, as is indicated in FIG. 7. Also, weather stripping comprised of vertical strip segments 78 and horizontal strip segments 79 is placed around the entire peripheral edge of each of the openings 6 on the outer face of wall 2. Strips of polyurethane adhesively secured to the outer face of wall 2 around openings 6 have been found to be quite satisfactory for this purpose.

From the foregoing description, it will be understood that panel unit 8 can be slidably shifted back and forth along track 10 by means of roller units 44 to align either closure panel sections 14 or ventilating panels 16 with openings 6. When it is desired to provide a weather tight, insulating closure over openings 6, panel unit 8 is shifted along track 10 to the position shown in FIG. 2 wherein air impervious, heat insulating panels 14 are aligned with openings 6. With latch arms 60 in their outward release positions, springs 66 are hooked

over attachment pins 70 within recesses 68. Latch arms 60 are then swung inwardly away from closure panel unit 8 and snapped into their locking positions shown in FIGS. 5 and 7. With springs 66 thereby placed in tension, the pairs of upper and lower latch devices will pull closure panel sections 14 inwardly toward wall 2 with angle iron frame members 18 around the periphery thereof bearing against weather stripping 78, 79 in tight, sealing engagement therewith. When it is desired to shift panel unit 8 to its open position with ventilating panel section 16 in alignment with openings 6, latch arms 60 are pivoted outwardly to their release positions to unload springs 66, which are then unhooked from pins 70. Since panel unit 8 is suspended only at its upper end by pivot brackets 50 and is free hanging at its lower end, its lower end will tend to swing outwardly away from wall 2 when the latching devices are released. Panel unit 8 may then be shifted laterally along track 10 without binding against or damaging weather stripping 78, 79. As panel unit 8 is manually shifted back and forth on track 10, it may be pivoted farther outwardly away from wall 2 about pivot pins 52 by the operator, if desired, to insure that there will be no interference of the weather stripping 78, 79 with the sliding movement of panel unit 8.

Although I have described my closure and ventilating panel structure with respect to a preferred structural embodiment thereof, I anticipate that various changes may be made in the size, shape and construction of the components without departing from the spirit and scope of my invention as defined by the following claims.

What is claimed is:

1. A combined closure and ventilating wall structure comprising:

an upright wall comprised of a plurality of fixed, spaced apart solid wall sections defining therebetween a plurality of spaced apart openings separated by said solid wall sections; a guide track attached to said upright wall above said openings in a direction coextensive with the longitudinal extent of said wall and said openings; a shiftable panel unit suspended at its upper end by guide means engaging said track and shiftable back and forth thereon, the bottom end of said panel unit being normally free hanging, and said panel unit being comprised of alternate, air impervious, heat insulating panel sections and air pervious ventilating panel sections joined together and shiftably movable back and forth together as a unitary assembly on said track between a first closed position in which said air impervious panel sections are aligned over said openings in closing relation thereto and a second, open position in which said ventilating panel sections are aligned over said openings;

weather stripping extending around the peripheral edge of each of said openings on the outer face of the portions of said wall sections defining said openings; and

latch means attached to said solid wall sections inside of each of said openings on opposite sides thereof, and cooperating attachment means on opposite sides of each of said air impervious panel sections with which said latch means are releasably engageable in such a manner as to pull said air impervious panel sections inwardly with the periphery thereof

against said weather stripping around said openings in tight, sealing engagement therewith.

2. A combined closure and ventilating wall structure as defined in claim 1 wherein:

said attachment means comprises retainer elements contained in recesses in the inside faces of said air impervious panel sections to thereby avoid interference of said panel unit with said weather stripping as a said panel unit is shifted between said open and closed positions.

3. A combined closure and ventilating wall structure as defined in claim 1 wherein:

said guide means comprise pivot bracket means connected between the top of said panel unit and guide elements shiftably engaging said track, said panel unit being swingable outwardly away from said upright wall about a substantially horizontal axis defined by said pivot bracket means whereby said panel unit may be swung outwardly away from said upright wall to avoid interference with said weather stripping as said panel unit is shifted along said guide track between said open and closed positions.

4. A combined closure and ventilating wall structure as defined in claim 1 wherein:

said latch means comprises a pair of vertically spaced latching devices adjacent to the top and bottom ends of each of said openings on both sides thereof, and said cooperating attachment means are positioned at the top and bottom of the inside peripheral faces of each of said air impervious panel sections on opposite sides thereof for engagement by said latching devices, whereby said air impervious panel sections may be tightly pulled in against said weather stripping at their upper ends as well as at the free hanging bottom ends thereof.

5. A combined closure and ventilating wall structure as defined in claim 1 wherein:

each of said latch means incorporates a normally unloaded spring which is releasably engageable with one of said attachment means on said air impervious panel sections, and a latch mechanism connected to one of said springs and shiftable towards and away from said panel unit in a plane generally normal thereto from a first, outwardly shifted release position to a second, inwardly shifted locking position in an inward direction away from said panel unit in which it places one of said springs in tension and pulls said air impervious panel sections in tightly against said weather stripping in tight, weather sealing contact therewith.

6. A combined closure and ventilating wall structure as defined in claim 5 wherein:

each of said latch mechanisms is a pivotal arm pivotally attached at its inner end to the side wall defining one of said openings for pivotal movement about a vertical axis, and each of said springs is connected to one of said arms at a point outwardly thereon from its point of pivotal attachment to one of said opening side walls, whereby said latch arms will snap into said locking position and hold said air impervious panel sections tightly against said weather stripping when said point of spring attachment to said arms goes over center with respect to said pivotal axes.

7. A combined closure and ventilating wall structure as defined in claim 6 wherein:

each of said latch means includes longitudinally adjustable coupling means between said springs and said latch arms, whereby the tension of said springs may be adjusted.

8. A combined closure and ventilating wall structure as defined in claim 1 wherein:

each of said air impervious panel sections is comprised of an opaque, thermal insulating sheet having at least one through aperture of decorative configuration therein, and a sheet of air impervious, translucent material overlying said thermal insulating sheet on at least one side thereof, whereby weather elements will be excluded by said air impervious sheet and light may pass only through the portions of said air impervious panel sections defined by the apertures in said opaque sheet.

9. A combined closure and ventilating wall structure as defined in claim 8 wherein:

said opaque, thermal insulating sheet is polyurethane and is sandwiched between two sheets of said translucent, air impervious material.

10. A combined closure and ventilating wall structure as defined in claim 1 wherein:

said guide means are attached only to the upper ends of said air impervious panel sections, and said ventilating panel sections have peripheral frames which are attached to abutting portions of said air impervious panel sections.

11. A combined closure and ventilating wall structure comprising:

an upright wall comprised of a plurality of fixed, spaced apart solid wall sections defining therebetween a plurality of spaced apart openings separated by said solid wall sections;

guide track means attached to said upright wall adjacent said openings in a direction coextensive with the longitudinal extent of said wall;

a panel unit shiftably supported by guide means engaging said track means for back and forth movement thereon, said panel unit being comprised of alternate, air impervious panel sections and air pervious ventilating panel sections joined together and shiftably movable back and forth as a unitary assembly on said guide track means between a first closed position in which said air impervious panel sections are aligned over said openings in closing relation thereto and a second, open position in which said ventilating panel sections are aligned over said openings; and

each of said air impervious panel sections is comprised of an opaque, thermal insulating sheet having at least one through aperture of decorative configuration therein, and at least one sheet of air impervious, translucent material overlying said insulating sheet on one side thereof, whereby weather elements will be excluded by said air impervious sheet and light may pass only through the portion of said air impervious panel sections defined by said aperture; and

weather stripping extending around the peripheral edges of each of said openings on the outer face of the portions of said wall sections defining said openings for engagement by the inner faces of said air impervious panel sections.

12. A combined closure and ventilating wall structure as defined in claim 11 wherein:

said opaque, thermal insulating sheets are polyurethane and are sandwiched between two sheets of translucent, air impervious material.

13. A combined closure and ventilating wall structure as defined in claim 11 wherein:

latch means are attached to said solid wall sections inside of each of said openings on opposite sides thereof and cooperating attachment means are positioned on opposite sides of each of said air imper-

vious panel sections on the inside faces thereof for releasable engagement by said latches means in such a manner that said latch means may be utilized to pull said air impervious panel sections inwardly against said weather stripping around said openings in tight, sealing engagement therewith when said panel unit is shifted to said closed position.
